UNITED STATES PATENT OFFICE

118,827

DESIGN FOR A WHEEL LOAD SCALE

David Middleman, Towson, Md., assignor to The Black and Decker Manufacturing Company, Towson, Md., a corporation of Maryland

Application November 10, 1939, Serial No. 88,201

Term of patent 14 years

To all whom it may concern:

Be it known that I, David Middleman, a citizen of the United States of America, residing in Towson, Baltimore County, State of Maryland, have invented a new, original, and ornamental Design for a Wheel Load Scale, of which the following is a specification, reference being had to the accompanying drawing, forming part thereof.

In the drawing:

Fig. 1 is a front perspective view of a wheel load scale showing my new design; and

Fig. 2 is an end perspective view thereof.

I claim:

The ornamental design for a wheel load scale, as shown.

DAVID MIDDLEMAN.
